UNITED STATES PATENT OFFICE.

JOHN E. PREST, OF NORTHBIDGE, MASSACHUSETTS.

DROP-WIRE STOP MECHANISM FOR WARPING-MACHINES.

SPECIFICATION forming part of Letters Patent No. 402,278, dated April 30, 1889.

Application filed September 17, 1888. Serial No. 285,585. (No model.)

To all whom it may concern:

Be it known that I, JOHN E. PREST, of Northbridge, in the county of Worcester, State of Massachusetts, have invented a certain new and useful Improvement in Drop-Wire Stop Mechanism for Warping-Machines, of which the following is a description sufficiently full, clear, and exact to enable any person skilled in the art to which said invention appertains to make and use the same, reference being had to the accompanying drawings, forming part of this specification, in which—

Figure 1 is a front elevation showing a group of drop-wires as ordinarily mounted, the bar being represented as broken off; Fig. 2, a side elevation of the same, the bar being shown in vertical transverse section; Fig. 3, a view similar to that in Fig. 1, showing my improvement; and Fig. 4, a side elevation showing my improved drop-wires in use, the bar being represented in vertical transverse section.

Like letters and figures of reference indicate corresponding parts in the different figures of the drawings.

My invention relates especially to means for mounting the drop-wires in the supporting-bar; and it consists in certain novel features, as hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the supporting-bar; B, the drop-wires; C, the lifting-bar, and D the vibrating bar of the stop-motion.

As ordinarily constructed, the supporting-bar A is provided with a thickened portion, x, on its lower edge, (see Fig. 2,) and a longitudinally-arranged dovetail groove, z.

A dovetail plate, m, is inserted in the groove z, the drop-wires B being pivoted to the upper portion of said plate in such a manner that their pivotal point i is outside the vertical center when said wires are in use. (See Fig. 2.) This arrangement of parts, however,

allows the oil, dirt, &c., to fall down behind the plate m and in a short time clog the hinge or pivot i of said wires to such an extent that they will fail to drop and strike the vibrating bar D when a thread, H, breaks. 55 Moreover, it largely increases the expense of construction to cut the groove z, and as the pivot i is outside the vertical center of the plate m, as described, the use of a stop-bar (not shown) to receive the wires as they fall 60 is necessitated.

My invention is designed to obviate these objections; and to that end I make use of means which will be readily understood by all persons conversant with such matters from 65 the following explanation.

The supporting-bar A in my improvement (see Fig. 4) is constructed without the thickened portion x, and has a groove, b, formed longitudinally in its face, said groove being 70 preferably rectangular in cross-section. A plate, d, is inserted in said groove, a plate, f, being secured to the face of the bar A and so arranged as to partially overlap said groove to retain said plate d in position therein. 75

The drop-wires B are hinged to the upper portion of the plate d by a pin, g, which is disposed inside the vertical center of the plate d, (see Fig. 4,) so that the upper edge of the groove b covers the slots h in the plate d, in 80 which said wires are pivoted. It will readily be seen that by this arrangement it is practically impossible for the wires B to become clogged at their hinges g by the dirt, &c., which accumulates from the yarn. Furthermore, 85 the body of the wires, being outside the pivotal point, assists greatly in causing them to fall when a thread, H, breaks.

The strip or plate f takes the place of the ordinary stop-bar, the wires B resting thereon, 90 as shown by the dotted line in Fig. 4, after having fallen sufficiently to engage the vibrating bar D of the ordinary stop-motion.

Having thus explained my invention, what I claim is—

1. In a drop-wire stop mechanism for warping-machines, the plate d, provided with the slots h, in combination with the wires B, pivoted in said plate with their bodies outside the pivoted point, and the supporting-bar A, 100

provided with the groove *b*, for receiving said plate, substantially as described.

2. In a drop-wire stop mechanism for warp-
ing-machines, a supporting-bar provided with
a longitudinal groove in its face, a plate in-
serted in said groove, drop-wires pivoted to
said plate and having their bodies outside the
pivotal point, and a retaining-plate secured

to the face of said bar for holding the drop-
wire plate therein, all being arranged to oper-
ate substantially as described.

JOHN E. PREST.
